UNITED STATES PATENT OFFICE

2,072,726

LATCH

Minas Yartyan, New York, N. Y.

Application March 18, 1936, Serial No. 69,459

11 Claims. (Cl. 292—37)

This invention relates to a device for latching or securing suitable appurtenances against movement in a particular position or any one of a number of different positions.

5 The device may be used advantageously in conjunction with a roll screen, curtain and the like. The device is useful, for instance, with a roll screen of the type disclosed in Letters Patent of the United States, No. 2,025,630, granted to me. 10 In this type of screen the screen material is wound on and unwound from a spring roller, and the opposite side edges of said material move in vertical guides respectively. The device of the present invention obviates the usual ratchet and pawl 15 of the roller, and will not only retain the screen material in position to fully occupy the window or door opening, but also serves to retain the screen material in different positions clear of desired portions of said opening.

20 The device enables a person to not only latch and unlatch an appurtenance, but also to operate or move the appurtenance, as for instance, the device will enable a person to unlatch a slideable screen, sash, curtain and the like, and to slide it down or up, or permit it to be drawn up by suitable means, and said device will automatically latch the screen, sash, curtain and the like upon release of the device.

25 The principal object of the invention is the provision of a device of the indicated character which is simple of construction; one which is of efficient and substantial design for the purposes mentioned; and one which may be produced at low cost.

30 The nature of the invention and its distinguishing features and advantages will appear when the following specification is read in connection with the accompanying drawings, in which:

35 Fig. 1 is an inside view of a roll screen applied to a window frame, said screen being selected to illustrate the device of the present invention shown applied for use therewith, and portions of the screen and the frame being broken away.

40 Fig. 2 is a fragmentary section showing certain features of the device.

45 Fig. 3 is a view looking down on the parts shown in Fig. 2.

50 Fig. 4 is a fragmentary section showing additional features of the device.

55 Fig. 5 is an enlarged sectional view taken on the line 5—5 of Fig. 1.

Fig. 6 is a sectional view taken on the line 6—6 of Fig. 4.

Fig. 7 is a perspective view of one of the parts 55 of the device used as a retainer.

Fig. 8 is a perspective view of a portion of the channel member showing the cam slots.

Fig. 9 is an enlarged sectional view taken on the line 9—9 of Fig. 1.

On reference to the drawings, it will be apparent that there is shown a supporting and guiding structure 10 arranged in a window frame 11. The structure 10 comprises a sill bar 12, a housing or casing 13, and tubular guides 14. The lower ends of the guides 14 are adjustably connected 10 with the bar 12 by adjusting screws 15 swivelly connected with said bar as at 16. The upper ends of the guides 14 are connected with the casing 13. The guides 14 are disposed vertically adjacent the side stiles of the frame 11, and each of said 15 guides has a slot 17 extending longitudinally thereof throughout its length. A spring roller 18 is arranged within the casing 13, and is operatively supported by suitable means which also serves to connect the casing 13 with the upper 20 ends of the guides 14. The casing 13 has an opening extending longitudinally and in communication with the upper ends of the slots 17 in the guides 14, so that screen material 19 connected with the roller 18 may be wound on the roller 25 and unwound therefrom while the opposite side edges of said material 19 moves in the slots 17 respectively. It is to be understood that the roller is under the influence of a rewinding spring 30 to rotate it in order to rewind the material 19 on said roller. The device of the present invention, by way of example, is applied to the lower end of the material 19, to not only retain the material 19 in position to fully occupy the window opening, but also to retain said material in 35 different positions clear of desired portions of said opening.

In accordance with the invention a metal strip 20 equal in length to the width of the screen material 19, together with additional metal strips 21 and 22 respectively of the same length as the strip 20, are secured to the lower end of the material 19 by suitable means such as the screws and nuts 23. The material 19 is bent around the strip 21 and said strip is arranged between the other strips 20 and 22, to thus effectually keep the material from pulling away from the strips. The strip 20 has a flange 24 extending along its lower edge throughout the length thereof. Said flange 24 projects inwardly beyond the strips 21 45 and 22. The opposite ends of all of the strips are notched as at 25 so as to project into the guides 14 respectively through their slots 17, and so as to clear the screws 15, in order that the flange 24 may be brought down in contact with 50 55

the sill bar 12. A metal channel member 26 of the same length of the flange 24 extends along and rests on said flange, the open side of the channel member 26 being closed by the flange. 5 Bearing blocks 27 are arranged within the channel member 26, there being four in the present instance, and two being disposed at the ends of the channel member respectively, and two near the middle thereof. The bearing blocks 27 are 10 removably retained in place by frictional contact with the opposite side walls of the channel member. Use is made of a pair of latch elements 28 constructed of cross-sectionally round stock. Each of said elements 28 consists of relatively 15 offset portions 29 and 30 respectively, and an intermediate portion 31 which joins the portions 29 and 30. The portions 29 and 30 are disposed parallel to each other, and the portion 31 is disposed at a right angle to the portions 29 and 30. 20 The portion 29 constitutes a latch portion, the portion 30 constitutes a handle portion, and the portion 31 constitutes a cam portion. Each of the elements 28 is supported by two of said bearing blocks 27 for movements with respect to said 25 channel member 26. The latch portion 29 of each element 28 is disposed within the channel member 26 and is received by the related bearing blocks 27 so as to move axially in opposite directions, and also to turn. The cam portion 31 projects through a cam slot 32 in the channel member 26, and the handle portion 30 is disposed outside of the channel member. When the latch portion is turning the portions 30 and 31 will each swing in an arc or vice versa. A tubular cross-sectionally round coupler constituting a handle is loosely connected or engaged with the handle portions 30 of the elements 28 so that said portions may have axial and turning movements with respect to said handle, the latter being designated 33. Each of the portions 30 projects only part way into the handle 33. Resilient means in the form of a coil compression spring 34 is arranged within the handle 33 and its opposite ends thereof bear on the handle portions 30 respectively. The spring 34 constantly 40 tends to urge the elements 28 away from each other into projected position for the latching or securing engagement of the latch portions 29, and said spring 34 permits the elements 28 to be moved toward each other into retracted position 45 for the disengagement of the portions 29. The walls of the slots 32 are disposed obliquely with respect to the axes of the latch portions, and constitute means fixed in relation to the cam portions 31 to cooperate therewith to cause the movement of the elements 28 toward each other wherein the latch portions 29 move axially and turn in the bearing blocks 27 when the handle 33 is being pulled into the position indicated in 50 dotted lines in Figs. 3 and 9, thereby disengaging the portions 29. Upon release of the handle 33 the spring 34 reacts and causing the elements 28 to move into their projected position for the engagement of the latch portions 29. These 55 portions 29 are in line with keeper strips 35 extending along the guides 14 respectively and secured thereto for relative adjustment by screw bolts 36 carried by each strip 35, and received respectively in longitudinal slots 37 in the related guide 14. Each strip 35 has a series of holes or slots 38 therein occurring from the lower end 60 up to approximately the middle of the strip, and said strip also has a comparatively long slot 39 therein near the casing 13. It will now be understood that the latch portions 29 may be en- 65

gaged with the strips 35 at different points by reason of the slots 38, to retain the screen material 19 in different positions clear of desired portions of the opening of the frame 11, and that said portions 29 may be engaged in the slots 39 respectively to prevent the material 19 being drawn up by the spring roller 18 beyond a certain point thereby stopping the latching assembly just below the casing 13. The screen material 19 will then be fully clear of the opening of the frame 11. By engaging the latch portions 29 in the lowermost notches 38 respectively, the flange 24 will be in contact with the sill bar 12 thereby excluding flies and insects, it being apparent that the material 19 will span the area bounded by the strips on the lower end of said material, the casing 13, and the guides 14. 10 15

It is to be understood that the channel member 26 may be secured in place in any suitable manner, or its equivalent be formed integral with the strip 20. The channel member 26 may be welded to the strip 20. In the present instance the channel member is secured in place by a pair of retainers 40, there being one retainer associated with each of the bearing blocks 27 at the ends of the channel member respectively. Each retainer 40 has a channel portion 41 formed on a plate portion 42. The portion 41 receives the end of the channel member with the block 27 resting on the bottom wall of the portion 41. The portion 42 has a hole 43 therein to receive a screw bolt 44 which also extends through aligned holes in the strips 20, 21 and 22. When the latch portions 29 are engaged with the strips 35, the retainers 40 will relieve the flange 24 of strain. 30 35

The strips 35 are vertically adjustable to compensate for adjustments of the sill bar 12 with respect to the guides 14 required to compensate for variations in the height of the frame construction. Thus it is possible to always bring the 40 flange 24 down in contact with the sill bar 12. 45

From the foregoing it will be obvious that a person may exert a pull on the handle 33 which will cause the disengagement of the latch portions 29 from the keeper strips 35, for winding or unwinding the material 19; that when the pull on the handle is withdrawn the latch portions 29 will be automatically engaged with the keeper strips 35 by the spring 34 to retain the screen material slid down to the desired extent; and that the other advantages mentioned may be attained. 50

I claim:

1. In a latch, latch members supported for movement into and out of latching position, resilient means acting on said latch members to urge them into their latching position, a handle loosely engaged with said latch members to move the latter in unison, and means fixed in relation to said latch members to cooperate therewith, as the handle is moved in one direction, to thereby move the latch members out of their latching position. 55
2. In a latch, latch members supported for movement into and out of latching position, a coil compression spring acting on said latch members to urge them into their latching position, a handle loosely engaged with said latch members to move the latter in unison, and means fixed in relation to said latch members to cooperate therewith, as the handle is moved in one direction, to thereby move the latch members out of their latching position. 65
3. In a latch, latch members supported for movement into and out of latching position, resilient means acting on said latch members to 70

75

urge them into their latching position, a coupler constituting a handle slidably and turnably connected with said latch members to move the latter in unison, and means fixed in relation to said latch members to cooperate therewith, as the handle is manipulated, to thereby move the latch members out of their latching position.

4. In a latch, latch members supported for movement into and out of latching position, a tubular coupler constituting a handle slidably and turnably connected with said latch members, a coil compression spring within said handle acting on said latch members to urge them into their latching position, and means fixed in relation to said latch members to cooperate therewith, as the handle is manipulated, to thereby move the latch members out of their latching position.

5. In a latch, latch members, means supporting said latch members for axial movement in opposite directions and also for turning movement, a handle loosely engaged with said latch members, said latch members having axial and turning movement with respect to said handle, resilient means acting on said latch members to urge them axially into their latching position, and means fixed in relation to the latch members to cooperate therewith, as the handle is manipulated to turn the latch members, to thereby move the latter axially out of their latching position.

6. In a latch, a pair of elements each constructed of cross-sectionally round stock and consisting of relatively offset portions joined by an intermediate portion, the offset portions of each of said elements consisting of a latch portion and a handle portion, the intermediate portion of each of said elements consisting of a cam portion, means which receives the latch portions of said elements to support the latter for axial movement in opposite directions and also for turning movement, a tubular handle telescopically engaging the handle portions of said elements, so that the latter may have axial and turning movements with respect to said handle, a coil compression spring arranged within said handle whose opposite ends bear on the handle portions of said elements respectively, and means fixed in relation to said cam portions of said elements to cooperate therewith, as the handle is moved to turn said elements, to thereby move the latter axially to disengage said latching portions against the compression of said spring, and the spring serving to urge said elements axially to engage said latch portions when the handle is released.

7. In a latch, slidable and turnable latch elements, resilient means to urge said elements into latching position, and a coupler constituting a handle slidably and turnably connected with said elements manipulatable to move said elements into unlatching position.

8. In a latch, slidable and turnable latch elements, resilient means to urge said elements into latching position, and a coupler constituting a handle slidably and turnably connected with said elements manipulatable to move said elements into unlatching position.

9. A latching assembly comprising a channel member, bearings in said channel member, ele-

ments having latch portions extending in said channel member and received in said bearings whereby said elements are supported for sliding and turning movements, said elements having handle portions disposed outside of the channel member, a tubular handle whose opposite ends slidably and turnably receive said handle portions respectively for the purpose of turning said elements and allowing the latter to slide with respect to said handle, resilient means within said handle which constantly acts on said handle portions to slide said elements into projected position to engage said latch portions, and cooperative means embodied by said channel member and elements to cause the latter to slide into retracted position to disengage said latch portions, when turning movement is imparted to said elements in response to the movement of said handle.

10. A latching assembly comprising a channel member, bearings in said channel member, elements having latch portions extending in said channel member and received in said bearings whereby the elements are supported for sliding and turning movements, said elements having handle portions disposed outside of the channel member, a tubular handle whose opposite ends slidably and turnably receive said handle portions respectively for the purpose of turning said elements and allowing the latter to slide with respect to said handle, resilient means within said handle which constantly acts on said handle portions to slide said elements into projected position to engage said latch portions, said channel member having slots therein disposed obliquely with respect to the axis of said latch portions, and said elements having cam portions extending through said slots respectively, said cam portions coating with the walls of said slots to cause said elements to slide into retracted position to disengage the latch portions, when turning movement is imparted to said elements in response to the movement of said handle.

11. A latching device comprising a rigid strip adapted to be attached to a structure mounted for movement, said strip having a flange extending along its lower edge, a channel member extending along said flange and resting thereon, bearings in said channel member, elements having latch portions extending in said channel member and received in said bearings whereby said elements are supported for sliding and turning movements, said elements having handle portions disposed outside of said channel member, a tubular handle whose opposite ends slidably and turnably receive said handle portions respectively for the purpose of turning said elements and allowing the latter to slide with respect to said handle, resilient means within said handle which constantly acts on said handle portions to slide said elements into projected position to engage said latch portions, and cooperative means embodied by said channel member and elements to cause the latter to slide into retracted position to disengage said latch portions, when turning movement is imparted to said elements in response to the movement of said handle.

MINAS YARTYAN.
